UNITED STATES PATENT OFFICE.

LEONARD C. KEMMING, OF DENISON, IOWA.

ROTARY VALVE FOR GAS-ENGINES.

1,134,461.

Specification of Letters Patent. Patented Apr. 6, 1915.

Application filed June 14, 1912, Serial No. 703,723. Renewed October 1, 1914. Serial No. 864,529.

To all whom it may concern:

Be it known that I, LEONARD C. KEMMING, citizen of the United States, residing at Denison, in the county of Crawford and State of Iowa, have invented certain new and useful Improvements in Rotary Valves for Gas-Engines, of which the following is a specification.

This invention relates to internal combustion engines, and has for its object the provision of a valve so constructed that a single valve will control the intake and exhaust of all the cylinders.

Incidental objects of the invention are to provide a construction whereby the valve will fit gas-tight against its seat, while at the same time it will be permitted to rotate easily, so as to attain the desired efficient operation.

The invention also seeks to improve, generally, the construction and arrangement of the controlling valve of multiple-cylinder engines, whereby the cost of production and maintenance will be reduced.

The invention is fully illustrated in the accompanying drawings, and will be herein-after first fully described and then more particularly pointed out in the appended claim.

In the drawings:—Figure 1 is a longitudinal section of a multiple-cylinder engine equipped with my improved valve; Fig. 2 is a transverse section of the same; Figs. 3, 4, 5, and 6 are enlarged diagrammatic transverse sections showing the position of the valve as though taken, respectively, on the lines 3—3, 4—4, 5—5, and 6—6 of Fig. 1.

The engine cylinders, 1, will be preferably cast as one integral body and may be of any well-known form, a head or heads 2 being fitted on the upper ends of the cylinders so as to extend over the same, and the heads are constructed with inlet passages 3 and exhaust passages 4, which are disposed opposite each other and extend diametrically across the ends of the cylinders. The inlet and exhaust passages for each cylinder communicate with the same through a common port 5 in the upper end thereof, as shown most clearly in Fig. 2, and the heads are constructed with a partition 6 bridging the inner ends of the inlet and exhaust passages and forming, with the upper ends of the cylinders, a tapered valve seat, as shown most clearly in Fig. 1.

The valve consists of a tapered body 7 fitting against and within the said tapered valve seat, sufficiently snug to form a gas-tight joint therewith, but, at the same time, capable of rotating easily within the seat. The valve may be solid or hollow, as preferred, but, if hollow, should have sufficiently thick walls to withstand long continuous wear.

In the exterior of the valve are formed recesses or depressions 8, which are so located as to register with the upper ends of the respective cylinders. These recesses or depressions are preferably constructed with curved bases, and each extends through one fourth of the circumference of the valve, so that, when one end or edge of the recess or depression registers with the port 5 in the top of the cylinder, the opposite end of said recess or depression will register with the inlet or exhaust passage, the said depression or recess in the valve thereby establishing communication between the cylinder and the inlet or exhaust port, as will be readily understood.

The recesses 8 extend only part way around the valve body and are successively located at different points around the said body, as will be readily understood, so that the positions of the said recesses will correspond to the positions of the pistons in the respective cylinders and to the cycle of operation of the cylinders, that is to say, in an engine having four cylinders, each recess or depression will be located in a different quadrant of the valve from each of the other recesses, and each quadrant of the valve will contain but one recess.

The valve body is, of course, tapered to correspond to the tapered formation of the valve seat, and at one end of the series of cylinders is an extension 9 having an adjusting screw 10 mounted in its end, said screw being provided with a plate or head 11 at its inner end; between which and the adjacent end of the valve, are a series of anti-friction devices 12 constituting an end thrust bearing for the valve, which will prevent axial movement of the valve but permit its free and easy rotation. At the opposite end of the cylinder is a threaded tubular extension 13, upon which is fitted a cap 14, and the valve is constructed with a stem or short shaft 15 extending through the said extension 13 and journaled in the cap 14, a spring 16 being coiled around the said

stem between the cap 14 and a disk or head 17 adjacent the end of the valve, so that the said disk or head will be yieldingly held toward the valve to prevent endwise movement of the same. Anti-friction devices 18 are fitted between the disk or head 17 and the end of the valve, so as to permit the easy rotation of the same, and the cap 14 may be adjusted longitudinally of the extension 13 to vary the tension of the coiled spring, so that the valve will be held to its seat with the pressure necessary to the particular engine.

The valve may be rotated through any desired or convenient form of valve gearing, and in the present instance, I have illustrated a bevel pinion 19 secured on the end of the shaft 15 and meshing with a pinion 20 on the upper end of a shaft 21 which is 20 geared directly to the crank shaft 22 of the engine, the several members being so proportioned that the valve will rotate at one-half the speed of the crank shaft.

It will be noted, upon reference to Fig. 1, 25 that the port 5 in the upper end of the cylinder extends approximately entirely across the same, so that it will accommodate the passage of a large volume of the gas and consequently an adequate supply for the 30 proper operation of the engine will be admitted to the cylinder. In Figs. 2 and 3, the valve is illustrated with the recess or depressed therein extending across the inlet passage 3, the intake stroke having been 35 completed and the port 5 being closed. The engine having been started, the valve will, of course, rotate and with respect to any one cylinder the said recess 8 will be successively carried to the positions shown in Figs. 40 4, 6, and 5, Fig. 4 showing an unutilized portion of the periphery of the valve extending across the port 5 in the cylinder and the recess 8 diametrically opposite said port which is, consequently, closed during the 45 compression and the explosion or working strokes. The port will remain closed or blocked by the valve during the explosion stroke, which is the position illustrated in Fig. 6, and the continued rotation of the 50 valve will cause the recess or depression therein to establish communication between the cylinder and the exhaust passage 4 through the port 5 and then move across said port, as shown in Fig. 5. During the 55 intake stroke of the piston, the valve will move from the position shown in Fig. 5 to that shown in Fig. 3 and, obviously, during that movement will establish communication between the passage 3 and port 5 to 60 permit a charge of fuel to enter the cylinder. During the exhaust stroke, the recess 8 moves from the position shown in Fig. 6 to that shown in Fig. 5, establishing communication between the cylinder and the exhaust passage as the stroke starts and cuts

ting off such communication as the stroke closes.

It will thus be seen that a single valve controls the inlet and exhaust of all the cylinders, and that the inlet to and exhaust 70 from each cylinder is direct, rapid, and efficient.

It is obvious from the foregoing description, taken in connection with the accompanying drawings, that the number of parts necessary with the constructions and arrangements of valves commonly employed is greatly reduced by my invention, and that the frictional resistance to the operation of the parts is likewise reduced. As the valve 80 rotates continuously, there is, of course, no jarring or pounding noise occasioned by its operation, and the comfort or pleasure of persons occupying the automobile equipped 85 with the invention is enhanced.

The construction permits the use of large valve openings, so that free passages are provided to and from the intake and exhaust manifolds, and consequently an increased power is derived from the engine. 90 The tapered formation of the valve overcomes all necessity for grinding the same to permit it to fit its seat, and wear on the valve may be compensated by adjusting the screw 10, whereupon the spring 11 may expand and shift the valve slightly axially, so that, as the valve wears it will fit more closely and smoothly against its seat. As the valve is constantly rotating upon its seat and is in constant contact therewith, carbon 95 deposits cannot accumulate on the valve to choke the same, and the device is not liable to get out of order. By varying the size of the valve, the openings for the passage of the gases may be made any desired size, 100 and the valve is, consequently, especially adapted to motors employed to perform heavy service.

What I claim is:—

In an internal combustion engine, the 110 combination of a plurality of cylinders arranged side by side, a head extending over all the cylinders and provided with a single admission port at the end of each cylinder and with inlet and outlet tubes extending 115 transversely from its opposite sides over each cylinder and terminating immediately adjacent the admission port in the end of the cylinder, a rotary valve mounted in the said head immediately over the admission 120 ports in the cylinders and between the inlet and outlet tubes of the same, said valve having both its ends and its entire circumferential surface closed to the admission 125 of fluid and provided in its circumferential surface with spaced recesses adapted to successively register with the admission ports in the respective cylinders, tubular extensions at the ends of the head, an adjustable thrust bearing mounted in one of said 130

tubular extensions and engaging the adjacent end of the valve, a shaft extending from the opposite end of the valve, a disk loose upon said shaft, a cap adjustably mounted on the adjacent tubular extension of the head and providing a bearing for said shaft, a spring coiled around the shaft within said extension between said cap and

said disk, and valve-operating gearing connected with said shaft.

In testimony whereof I affix my signature in presence of two witnesses.
